US00D875709S

(12) **United States Design Patent** (10) **Patent No.:** **US D875,709 S**
(45) **Date of Patent:** **** Feb. 18, 2020**

(54) **EARPHONE**

(71) **Applicant:** **SHENZHEN GRANDSUN ELECTRONIC CO., LTD.**, Shenzhen, Guangdong (CN)

(72) **Inventors:** **Xin Yuanfa**, Shenzhen (CN); **Wu Haiquan**, Shenzhen (CN); **Yu Xin**, Shenzhen (CN); **Shi Ruiwen**, Shenzhen (CN)

(73) **Assignee:** **SHENZHEN GRANDSUN ELECTRONIC CO., LTD.**, Shenzhen, Guangdong (CN)

(**) **Term:** **15 Years**

(21) **Appl. No.:** **29/655,669**

(22) **Filed:** **Jul. 5, 2018**

(30) **Foreign Application Priority Data**

Jan. 5, 2018 (CN) 2018 3 0004836

(51) **LOC (12) Cl.** **14-01**

(52) **U.S. Cl.**

USPC **D14/205**

(57) **CLAIM**

The ornamental design for earphone, as shown and described.

DESCRIPTION

FIG. 1 is a perspective view of an earphone;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of another embodiment of an earphone;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of another embodiment of an earphone;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The design which is claimed is shown in solid lines in the drawings. The broken lines depict environment that forms no part of the claimed design.

1 Claim, 21 Drawing Sheets
